CLOTH-BOARD REEL

Joseph T. Yovanovich, Rosemont, Pa., assignor to National Tube and Reel Corporation, Belleville, N.J., a corporation of New Jersey

Filed Oct. 8, 1965, Ser. No. 494,071

8 Claims. (Cl. 206—50)

This invention relates generally to reels, and is especially concerned with improvements in cloth-board reels, as for carrying cloth wound thereabout.

As is well known to those versed in the art, cloth has for years been conventionally wound on reels fabricated of wood. Relatively sturdy, heavy and expensive wooden reels were necessary to withstand the torsional and buckling stresses imparted during machine-winding of cloth on the reels. It has been proposed to fabricate cloth-board reels of less expensive construction and materials, as of paper stock and the like, but such attempts have not been entirely satisfactory. For example, prior cloth-board reels fabricated of paper stock in a manner to compete economically have not proved reliably staunch and sturdy under all conditions of use.

Accordingly, it is an important object of the present invention to provide a cloth-board reel adapted to be inexpensively fabricated of paper stock, or other suitable material, which is extremely staunch, durable and reliable under all conditions of use, to resist torsional and buckling stresses applied during machine-winding of cloth on the reels.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a plan view showing a cloth-board reel constructed in accordance with the teachings of the present invention, and partly broken away for clarity of illustration;

FIGURE 2 is a transverse sectional view taken generally along the line 2—2 of FIGURE 1; and

FIGURE 3 is a perspective end view showing a cloth-board reel of the present invention in operative association with a coil of cloth.

Referring now more particularly to the drawings, and specifically to FIGURE 3 thereof, a cloth board is there generally designated 10, and is of generally flat, substantially rectangular configuration, having wound thereabout a coil of fabric 11.

The cloth board 10 is illustrated in greater detail in FIGURES 1 and 2, and may be substantially entirely fabricated of paper stock, such as thin cardboard or the like, including a generally rectangular, substantially flat intermediate panel or sheet 13 which may have its opposite faces coated with adhesive, as at 14. Arranged in congruent overlying relation with the intermediate or central panel 13 is an upper stiffener sheet 15. The upper stiffener sheet 15 is of generally rectangular-outline configuration, generally equal in size to that of the intermediate sheet 13 and superposed on the upper face thereof. Formed in the upper stiffener sheet 15 are a series of parallel corrugations 16 extending diagonally entirely across the sheet. Specifically, the corrugations 16 extend obliquely approximately 45 degrees to the longitudinal direction of the stiffener sheet 15. As best seen in FIGURE 2, the corrugations 16 of stiffener sheet 15 are of generally rectangular cross-sectional configuration, each

2

having a generally flat outer portion or crest 17 of generally rectangular configuration, and a generally flat inner portion or trough 18, also of generally rectangular configuration. The crests 17 and troughs 18 are connected together by generally parallel side walls 19 extending between and generally normal to the crests and troughs.

It will therefore be apparent that the troughs or inner portions 18 of corrugations 16 have generally rectangular lower surfaces or areas in facing, adhesively secured engagement with the upper surface of intermediate sheet 13, as by the upper adhesive layer 14.

A lower or under stiffener sheet 20 is of generally rectangular outline configuration, substantially congruent and arranged in facing relation with the underside of intermediate panel 13. The lower stiffener sheet 20 may also be of flexible paper stock or other suitable material, and is formed with parallel corrugations 21 extending diagonally across the sheet. The corrugations 21 extend obliquely approximately 45 degrees to the longitudinal direction of the stiffener sheet 20, and approximately 90 degrees to the corrugations 16 of the upper stiffener sheet. In both the upper stiffener sheet 15 and lower stiffener sheet 20, the respective corrugations thereof occupy substantially the entire sheet. Further, the corrugations 21 of the lower stiffener sheet 20 are configured to be of generally rectangular cross section, thereby defining generally flat outer portions or crests spaced from the intermediate sheet 13, and generally flat inner portions or troughs 23 in adjacent facing relation with the intermediate sheet. Each of the crests 22 and troughs 23 is of generally rectangular, substantially flat surface configuration, and the crests and troughs are connected together by side walls 24 extending between and generally normal to the crests and troughs. The generally rectangular surface areas of the troughs 23 are adhesively secured in surface engagement with the underside of intermediate sheet 13 by the lower adhesive layer 14.

Circumposed about the adhesively secured assemblage of intermediate sheet 13 and upper and lower stiffener sheets 15 and 20, is a wrapper sheet 26. The wrapper sheet 26 may be of generally rectangular-outline configuration and circumscribed about the intermediate and stiffener sheets 13, 15 and 20, having portions lying in facing engagement with the generally rectangular areas of crests 17 and 22. Further, the inner surface of wrapper sheet 26 may be coated with adhesive 27 serving to firmly secure the wrapper sheet to the rectangular surface areas of the corrugation crests 17 and 22. The wrapper sheet may be coextensive with the intermediate and stiffener sheets 13 and 15, longitudinally thereof, and may have overlapping edge portions 28 and 29 adhesively secured together to define a seam extending longitudinally between opposite ends of the assembly.

As thus far described, the cloth-board reel 10 has its intermediate sheet 13 and stiffener sheets 15 and 20 exposed at the ends. To cover and further stiffen the assembly, an ovaloid endpiece 30 is engaged in covering relation across each exposed end of the assembled sheets. The endpiece 30 may include a pair of flaps 31, each swingable into overlying facing engagement with the adjacent portion of wrapper sheet 26 and adhesively secured thereto. Each ovaloid endpiece 30 and its adjacent flaps may be integrally fabricated, say of cardboard, or the like, the flaps being hingedly connected to the endpiece, as by score lines. This end construction adds staunchness to the entire assembly, as well as serving to resist local damage at the end regions.

For unity of structure and identification, a paper label may be extended across each endpiece 30, and wrapped about the adjacent flaps 31 and portion of wrapper sheet 26, being adhesively secured in its wrapped condition.

It will now be appreciated that the rectangular cross-

sectional configuration of corrugations 16 and 21 provides rectangular crest and trough surfaces of substantial area for firm, reliable adhesive securement to the wrapper and intermediate sheets 26 and 13. This unitary structure is further rigidified by the oblique directions of corrugations 16 and 21, as well as securement of endpieces 30 and flaps 31. In addition, strength is further enhanced by employing paper stock having grain extending in the longitudinal direction of the reel. Thus, the grain of the intermediate sheet 13, stiffener sheets 15 and 20, and wrapper 26, may all advantageously extend longitudinally of the resultant assembly, for increased resistance to buckling.

Although the present invention has been described in some detail by way of illustration and example for purposes of clarity of understanding, it is understood that certain changes and modifications may be made within the spirit of the invention and scope of the appended claims.

What is claimed is:

1. A cloth-board reel fabricated of flexible sheet material and comprising a longitudinally extending generally flat intermediate sheet, a first longitudinally extending stiffener sheet generally congruent with and adhesively secured to one face of said intermediate sheet, said first stiffener sheet having corrugations of generally rectangular cross-sectional configuration and extending obliquely across said first stiffener sheet, a second longitudinally extending stiffener sheet generally congruent with and adhesively secured to the other face of said intermediate sheet, said second stiffener sheet having corrugations of generally rectangular cross-sectional configuration and extending obliquely across said stiffener sheet transversely of the first-stiffener-sheet corrugations, and a wrapper sheet extending circumferentially about said intermediate and first and second stiffener sheets and adhesively secured to the corrugations of said stiffener sheets.

2. A cloth-board reel according to claim 1, said first and second stiffener-sheet corrugations extending obliquely generally 45 degrees to the longitudinal dimension of said stiffener sheets.

3. A cloth-board reel according to claim 1, said first and second stiffener-sheet corrugations having generally flat crests and troughs defining generally rectangular areas adhesively secured in facing engagement with said intermediate and wrapper sheets.

4. A cloth-board reel according to claim 1, said wrapper sheet comprising an integral generally rectangular piece

having overlapping edge portions adhesively secured together and defining a longitudinally extending seam.

5. A cloth-board reel according to claim 4, in combination with an elongate endpiece over each set of adjacent ends of said intermediate and stiffener sheets, and flaps on each of said endpieces and secured to said wrapper sheet.

6. A cloth-board reel according to claim 5, in combination with a label sheet adhesively secured in enveloping relation with each endpiece, its adjacent flaps and the adjacent portion of said wrapper sheet.

7. A cloth-board reel fabricated of flexible sheet material and comprising a longitudinally extending generally flat intermediate sheet, a first longitudinally extending stiffener sheet generally congruent and in facing relation with one face of said intermediate sheet, said first sheet having corrugations of generally rectangular cross-sectional configuration extending across said stiffener sheet generally 45 degrees to the longitudinal dimension thereof and defining generally rectangular areas of troughs in facing engagement with said intermediate sheet and generally rectangular areas of crests spaced from said intermediate sheet, a second longitudinally extending stiffener sheet generally congruent and in facing relation with the other face of said intermediate sheet, said second stiffener sheet having corrugations of generally rectangular cross-sectional configuration extending approximately 45 degrees obliquely across said second stiffener sheet transversely of said first-stiffener-sheet corrugations, said second-stiffener-sheet corrugations defining troughs of generally rectangular area in facing engagement with said intermediate sheet and crests of generally rectangular area spaced from said intermediate sheet, a wrapper sheet extending circumferentially about said intermediate and first and second stiffener sheets, and adhesive means securing said trough areas to said intermediate sheet and said crest areas to said wrapper sheet.

8. A cloth-board reel according to claim 7, said intermediate and first and second stiffener sheets being fabricated of paper, the grain of each of said sheets extending longitudinally thereof.
